UNITED STATES PATENT OFFICE

GEORGE L. PIERCE, OF BROOKLYN, NEW YORK, ASSIGNOR TO A. G. SPALDING & BROS., OF NEW YORK, N. Y., A CORPORATION OF NEW JERSEY

SHOE SOLE

Application filed March 25, 1931. Serial No. 525,263.

The invention relates to sole members for foot wear having combined therein a forward portion of rubber constituting the sole proper and its shank and a rear portion of leather 5 constituting a heel section or heel seat.

The invention concerns particularly the construction whereby these parts are interconnected so that the joint between them will extend at an angle to the normal transverse 10 line of flexure and the rubber shank will be reinforced and supported by the leather heel portion.

The invention is shown in the accompanying drawing in which

15 Figure 1 is a top plan view of the composite member.

Figure 2 is a bottom plan view.

Figure 3 is an edge view.

Figure 4 is a perspective view of the meeting ends of the shank and heel section.

Figure 5 is a detail.

In the drawing 1 is the sole proper composed of rubber and having a shank portion 2. At the rear end of the shank there is a leather 25 section 3 which constitutes the base or seat for the heel. These two parts are joined together by tapering the rear part of the shank portion upwardly from point *a* rearwardly to the thin edge *b*. The forward part of the leather 30 heel seat portion 3 is tapered downwardly to a thin edge to correspond with the taper on the shank. The heel section is formed V-shaped at this tapered forward portion to provide the inclined seat *c* for the tapered 35 rear portion of the shank, this seat being defined by the V-shaped forward end of the leather member at *d*. *e*. *f*. and by the line *g*. *h*. *i*.

The shank at its rear end has a formation 40 complementary to that of the forward end of the heel portion that is to say it has a re-entrant angular thin edge *j*. *k*. *l*. and an angular line *m*. *n*. *o*. corresponding to the end of the leather portion *d*. *e*. *f*. The two parts are 45 cemented or vulcanized together at their tapered surfaces to make substantially an integral body. In the ordinary flexing of the sole when in use the line or zone about which the bending of the composite member takes 50 place is transverse to the longitudinal axis of

the member. Were the joint between the two parts made on a line or zone at right angles to the longitudinal axis of the sole said joint would tend to open but with the V-shaped joint above described the lines thereof are at 55 an angle to the transverse line of bend and hence there will be no danger of the opening of the joint, the line of stress being across the line of the joint.

By my invention also the V-shaped extension of the heel seat portion projects at its 60 central part well under the rear portion of the shank from a point at the longitudinal center line thereof along diverging lines to the side edges so that support is afforded to 65 the shank and a strong construction is provided.

The heel section may be slit from *p* to *r* on 70 its under side so as to provide a thin layer of leather say 1/64 of an inch in thickness.

This may be turned forward in order that the heel of wood or other material may be attached to the heel section. Then this thin layer of leather may be laid against the breast of the heel and there cemented to finish 75 the heel of the shoe at this point. The heel section and the rubber sole portion may be additionally secured together by a line of stitching indicated at *s*.

The heel section may receive nails to secure 80 it in place and the rubber sole may be secured by a welt.

It will be observed that point *r* defines the line of the breast of the heel and that the taper of the forward extension of the heel begins at 85 a point in rear of the line or face of the heel breast and extends forwardly and downwardly in relation to said line and that the shank has a complementary taper on its under side lying upon the taper of the heel section so 90 that the rear end of the tapered portion of the shank extends to a point in rear of the point *r* and hence in rear of the breast line so that the tapered end of the shank is supported both by the forward extension of the 95 heel section and by said heel section itself.

I claim:

1. A shoe sole comprising a tread and shank portion, and a heel seat section, said heel section having its forward portion of V- 100

shape from side to side and tapered downwardly to a thin edge, the apex of the V shape being directed forwardly on the longitudinal center line of said heel seat section the shank having a formation at its rear end complementary to the forward end of the heel, said V-shaped and tapered ends of the shank and heel being secured together to act as one body, the forward V-shaped tapered part of the heel underlying the complementary shaped rear end of the shank and furnishing a support therefor.

5 2. A shoe sole having a tread and shank portion and a heel section intimately united therewith, said heel section being slit from its rear part forwardly to provide a thin layer of material to finish the breast of the heel, substantially as described.

15 3. A shoe sole according to claim 1 having a thin layer of material slit from but integrally united with the heel section and extending to near the V-shaped formation, said thin layer being adapted to finish the breast of the heel, substantially as described.

25 4. A shoe sole according to claim 6 in which the tread and shank portions are of rubber and the heel seat section is of leather, substantially as described.

35 5. A shoe sole comprising a tread and shank portion and a heel section, said heel section having an extension forwardly of the line of the breast of the heel, said extension being tapered downwardly and the plane of the tapered surface reaching to a point in rear of said breast line, the shank having a complementary upwardly tapered under surface and reaching to said point in rear of the breast line, said shank at its rear end therefore being supported both by the forward extension of the heel section and by said section at the rear of said breast line, substantially as described.

40 6. A shoe sole comprising a tread and shank portion and a heel section, said heel section having an extension forwardly of the line of the breast of the heel and tapered downwardly, the shank having a complementary upwardly tapered under surface overlying the said forward extension of the heel, substantially as described.

45 In testimony whereof, I affix my signature.
GEORGE L. PIERCE.
